DESIGN FOR A PIN

Adolph Frankenthaler and Stanley Rosenthal,
New York, N. Y.

Application February 20, 1941, Serial No. 99,125

Term of patent 3½ years

To all whom it may concern:

Be it known that we, Adolph Frankenthaler and Stanley Rosenthal, citizens of the United States and residing at 243 West End Avenue, New York city, in the county of New York, State of New York, and 200 Cabrini Boulevard, New York city, in the county of New York and State of New York, have invented a new, original, and ornamental Design for a Pin, of which the following is a specification, reference being had to the accompanying drawing forming part thereof.

We claim:

The ornamental design for a pin, as shown.

STANLEY ROSENTHAL.
ADOLPH FRANKENTHALER.
